SEWING MACHINE CABINET

Howard D. Stump, South Bend, Ind.

Application October 6, 1954, Serial No. 32,562

Term of patent 14 years

(Cl. D33—12)

Fig. 1 is a front perspective view of the sewing machine cabinet, showing my new design; and

Fig. 2 is an enlarged sectional view taken on line 2—2 of Fig. 1, portions thereof being broken away for convenience of illustration.

I claim:

The ornamental design for a sewing machine cabinet, as shown.
